CLAIM

The ornamental design for a fragrance cartridge, as shown and described.

DESCRIPTION

FIG. 1 is a perspective view, looking from above, of a fragrance cartridge showing our new design;

FIG. 2 is a right side elevational view thereof, the left side elevational view being substantially identical thereto;

FIG. 3 is a front elevational view thereof, the rear elevational view being substantially identical thereto;

FIG. 4 is a top plan view thereof; and

FIG. 5 is a bottom plan view thereof.

FIG. 1

FIG. 2

FIG. 3

FIG. 4

FIG. 5
